UNITED STATES PATENT OFFICE.

PETER K. DEDERICK, OF ALBANY, NEW YORK.

BALING-PRESS.

SPECIFICATION forming part of Letters Patent No. 251,421, dated December 27, 1881.

Application filed May 24, 1880. (No model.)

To all whom it may concern:

Be it known that I, PETER K. DEDERICK, of Albany, in the county of Albany and State of New York, have invented certain Improvements in Baling-Presses, of which the following is a specification.

This invention relates to that class of presses for which Letters Patent Nos. 132,566 and 132,639 were granted me October 29, 1872, and for which numerous other Letters Patent have been granted me since that date for improvements; and it consists in certain further improvements, which I will first describe, and then point out particularly in the claims.

15 In the accompanying drawings, Figure 1 is a perspective view of my improved machine. Figs. 2 and 3 are views of the power.

A represents the press-box of the press; B, the bale-chamber; C, the hopper; D, the traverser; E, a staff or slide-bar attached to the traverser; F, a pitman connecting the crank to the slide-bar E; G, the crank. I is an oval gear-wheel, to the shaft or axis of which the crank G is rigidly secured; and J is the power-wheel, 25 provided with a journal on its lower side, which rests in the frame, and having a shaft, K, projecting from its upper side and having its bearing in the cross-piece of the frame above. O is a lug-wheel mounted on the prolongation 30 of the shaft K; and P is the horse-lever or sweep, co-operating with said lug-wheel.

Heretofore in this class of presses the pitman has been connected at one end to the operating-crank and at the other end directly 35 to the traverser, and as in operation the pitman was given a vibratory motion it became necessary to bridge over the pitman, in order that the horses might safely walk over it without danger of having their legs knocked from 40 under them by its vibrations. This bridging, however, being a separate structure, lessened the portability of the press. Moreover, as the only connection between the power end of the press and the press-box was below the pitman, 45 such connections were required to be very strong and heavy.

The first objection to the old style of press I obviate by the use of the slide E. This slide is suitably guided, and has only an endwise 50 instead of a vibrating motion, so that the

horses can easily and safely step over it without the necessity of employing a bridge.

A close-fitting box may be placed over the slide, if desired, but it is not a necessity.

The slide may be firmly secured to the traverser, or may be articulated to it, as desired.

To further reduce the size of the connections between the power end of the press and the press-box, and thus enable the horse to cross with a shorter step, the plank R, running under the slide, is made of small dimensions, so that both plank and slide can be comprehended in a short step of the horse. The reducing of the dimensions of the plank R, however, without further provision would 65 weaken the connection so much that in the operation of pressing the plank would spring up in the middle and interfere with the proper operation of the press. The provision that I make to meet this difficulty is as follows: I secure two stout standards, S S, at or near the end of the press-box, and to them connect rods U U T T, said rods leading on the one hand from the body of the press proper and on the other hand from the upper end of the shaft K. 70 The manner of connecting the lower ends of the rods T T is immaterial, so long as it be done so that the horse-lever or sweep and the horse can pass around without interfering with them. The rods stiffen and brace the structure and render the buckling of the timber R 75 impossible.

Having thus described my invention, I claim as new—

1. The combination of the traverser, the pitman, and crank with the reciprocating slide forming the connection between the pitman and traverser, whereby the horses are enabled to pass the connections without being struck by a vibrating part, substantially as described. 85

2. The combination of the power end of the press with the press-box, the narrow connecting-plank, and the strengthening and staying rods connected to the press-box and to the power end of the press, substantially as described. 90

P. K. DEDERICK.
